Hers Attorneys.

UNITED STATES PATENT OFFICE

VIRGINIA P. NELSON, OF NEW YORK, N. Y.

COLLAPSIBLE CANOPY SUPPORT

Application filed December 2, 1931. Serial No. 578,494.

This invention relates to improvements in canopy supports, particularly of a type which may be mounted upon the wall over a bed or the like.

The general object of this invention is to provide an improved form of canopy or drapery support made in knock-down form so that it may be easily taken apart. The structure is of such a nature that the device may be mounted directly upon a wall and supported by the wall molding, for example, with the result that the device may be placed over any object in the room, such as a bed, a chair, or the like.

One of the advantages of a construction of this type is that it can be easily moved about the room and lends itself to employment in any number of suitable, decorative schemes.

Another object of the invention is the provision of a structure of this type which, while of a rugged construction, is at the same time capable of being taken apart or put together without difficulty, and hence further lends itself to ready storage when not in use.

These and many other objects, as will appear from the following disclosure, are secured by means of this invention.

This invention resides substantially in the combination, construction, arrangement, and relative location of parts, all as will be described in detail in connection with the drawing and set forth in the appended claims.

Referring to the drawing—

Figure 1 is a side elevational view of the device of this invention showing it mounted on a wall molding;

Fig. 2 is a front elevational view of the wall bracket;

Fig. 3 is a bottom plan view of the plate which supports the rotating ring supporting arms;

Fig. 4 is a detail view of the sockets which receive the ring forming bands; and

Fig. 5 is an end elevational view of this socket.

The device of this invention involves a simple structure upon which canopies or

draperies may be secured and from which they may hang or be draped in any suitable decorative manner. Devices of this nature are known for direct attachment to beds and the like for supporting draperies thereover. 55 The purpose of this invention is to provide a structure which need not be mounted upon the bed, but rather lends itself to mounting on the wall over the bed and hence provides a less conspicuous structure for supporting 60 the draperies, and also permits of mounting of the device in any part of the room.

Referring to the drawing, the wall line is indicated in Fig. 1, to which is secured the usual molding 2 that normally extends 65 around the room near the ceiling. The device itself comprises a support made up of a vertical portion 3, a horizontal rearwardly extending portion 4, and an upwardly extending portion 5. At the top is provided a 70 forwardly extending portion 6. All of these portions comprise an integral sheet or plate which, of course, may assume any desired decorative form without departure from the principles of this invention. The forwardly extending portion 6 is provided with two upwardly extending parallel wings 7 which may be struck up from the portion 6. The vertical portion 3 is provided with two socket members 8 and 9 which are likewise pressed 75 out of the material of the portion 3 and extend rearwardly thereof as is shown.

A right angle rod or arm comprising the portions 11 and 12 is provided of a size so that the portion 11 may slide down in the sockets 8 and 9, and the portion 12 may lie between the wings 7. The outer end of the arm 12 is provided with a ring in which is secured a plate 17 by means of a screw 14, a wing nut 15, and a washer 16. The plate 17 is provided with a series of sockets 18 formed therein and lying on the under surface thereof. Adjacent the inner ends of each of these sockets are struck up tabs 19. At the center of the plate 17 is a hole 17' through which the screw 14 passes. Each of the sockets 18 is provided with an arm 20 which fits thereinto and each of which is limited in its inward movement by means of 80 the tabs 19 which act as stops. The outer

ends of the arms 20 are bent downwardly at right angles thereto and have riveted thereto, as indicated at 21, sockets or clips 22. As is clear from Fig. 3 there are four of these arms 20, the outer end of each of which is provided with a socket or clip 22. Four flexible metal bands or strips 23 are provided which are snapped into the sockets, as indicated in Fig. 1, so as to form a circle or ring, as will be apparent to those skilled in the art.

As indicated at 10 two hooks are struck out of the body portion 3 and suitably formed so as to rest on the molding, as indicated in Fig. 1. The portion 3 is provided with a hole 3' through which a threaded bolt 25 passes. This bolt also passes through an L-shaped piece 24 which is provided with a vertical slot in the vertical portion. This L-shaped member 24 is adjustable in a vertical direction for a distance defined by the length of the slot therein and may be clamped in any one of a number of positions by means of the wing nut 26. The purpose of this L-shaped member is to support the inner end 25 of the ring shaped frame so that when the draperies are attached thereto it cannot be pulled out of a substantially horizontal position. The portion 6 prevents its movement in the other direction so that the ring shaped frame is supported substantially horizontally even though the draperies pull unevenly thereon. The rearwardly extending portion 4 resting against the wall acts to hold the entire structure in such a manner that the ring portion is horizontal.

As those skilled in the art know, the draperies are secured to the ring portion in any suitable manner so as to depend therefrom and will, when properly designed, substantially hide the fixture. From the above description it will be seen that the structure of this invention, while exceedingly simple and adapted to be readily taken apart and put together, is admirably adapted for the intended use and is of a nature to provide a rugged construction.

I am well aware that the principles of this invention and the details of construction may be readily varied by those skilled in the art without departing from the invention, and I do not therefore desire to be limited by the disclosure, except as set forth in the appended claims. For example, it is obvious to those skilled in the art that the invention is not limited to a bracket which may be attached to a molding, but may be in a form which can be attached to the wall by means of nails or screws. Furthermore, the drapery supporting frame need not be in circular form but may have some other configuration without departure from the invention.

What I seek to secure by Letters Patent is:

1. A canopy support adapted to be mounted upon a wall comprising a supporting plate having hooks thereon and a rearwardly ex-

tending spacing portion, a horizontally extending arm secured thereto, and a collapsible circular frame detachably secured to said arm.

2. A canopy support comprising a wall bracket having sockets formed thereon, an arm removably mounted in said sockets, and a drapery supporting frame detachably secured to said arm comprising a plate, a plurality of arms detachably secured to said plate, and a plurality of strips mounted on the outer ends of said arms to provide the drapery supporting frame.

3. A canopy support comprising a wall bracket having means thereon for mounting it on the wall, an arm detachably secured to said bracket, and a drapery supporting frame comprising a plate mounted on said arm having a plurality of sockets thereon, arms mounted in said sockets and radiating outwardly from the plate, and means secured to the outer ends of said arms to form a frame.

4. A canopy support comprising a wall bracket having means thereon for mounting it on the wall, an arm detachably secured to said bracket, and a drapery supporting frame comprising a plate mounted on said arm having a plurality of sockets thereon, arms mounted in said sockets and radiating outwardly from the plate, and a plurality of strips secured to the outer ends of said arms to form a frame.

5. A completely collapsible canopy support comprising a wall bracket having means thereon for mounting it on the wall, an arm detachably secured to said bracket, and a drapery supporting frame mounted on said arm comprising a plate having a plurality of sockets thereon, arms mounted in said sockets and radiating outwardly from the plate, socket members secured to the outer ends of said arms, and metal bands mounted in said socket members to form a frame.

6. A canopy support comprising a wall bracket having a rearwardly extending spacer portion and a forwardly extending lip, parallel wings formed on said lip, sockets formed on said bracket, an arm mounted in said sockets and lying between said wings, and a canopy supporting frame secured to the outer end of said arm.

7. A canopy support as described, comprising a wall bracket adapted to be mounted on a wall moulding and having spacer means at its lower end to support it parallel to the wall, and a collapsible canopy supporting frame detachably mounted thereon.

In testimony whereof I have hereunto set my hand on this 30th day of November A. D., 1931.

VIRGINIA P. NELSON.
